H. MEDDRUM

VAGINAL SYRINGE

Filed Sept. 14, 1925

UNITED STATES PATENT OFFICE.

HARRY MELDRUM, OF BROOKLYN, NEW YORK.

VAGINAL SYRINGE.

Application filed September 14, 1925. Serial No. 56,238.

This invention relates to a vaginal syringe.

The object of the invention is the production of a vaginal syringe, in which the 5 injection fluid is separated from the return or outflowing fluid. The second object of the invention is the production of a vaginal syringe, which can be easily dismantled to clean each of its parts. The third object 10 is the production of a syringe of simple parts that can easily be replaced and assembled, and which are of cheap first cost. The fourth object of the invention is the production of a syringe with an adjusting and 15 stop hood, which retains fluid in the vaginal canal, by means of which a pressure and suction can be obtained to loosen the folds of the canal to thoroughly clean every portion thereof. The fifth object is the production 20 of a vaginal syringe with an adjusting and stop hood to control the depth of its insertion in the vaginal canal.

In the accompanying drawings Fig. 1 represents a side elevation of an exemplification of the vaginal syringe with its appurtenances; Fig. 2 shows an enlarged cross section of Fig. 1 on the line 2, 2; Fig. 3 indicates a section of Fig. 2 on the line 3, 3, and Fig. 4 shows an end view of a detail.

The syringe in this instance is indicated with the injection tube 20, having the threaded ends 21 and 22. A tube fitting is indicated in its entirety at 24 and is shown with the corrugated inlet nipple 25, having 30 the axial inlet opening 26 and the corrugated outlet nipple 27 at one end, smaller in diameter than the inlet nipple 25 and the return fluid discharge chamber 28 at the other end. The end of the fitting 24 opposite the nipple 25 is counterbored as shown at 29. The threaded end 22 of the tube 20 is in threaded engagement with the wall of the opening 26. An outlet nozzle 35 has formed therein the discharge chamber 36 40 for the injection fluid and said chamber is threaded at one end for the threaded end 21 of the said injection tube 20. The nozzle has formed on its outer face a plurality of recesses 37, and small outlet openings 38 extend through the nozzle from the chamber 36 to the said recesses. A reduced portion 39 is formed with said nozzle.

An outer discharge tube 45 has one end detachably seated in the counterbore 29 of 45 the fitting 24, and its other end is detachably

seated on the reduced portion 39 of the nozzle 35. The said discharge tube has formed therewith a pair of oppositely positioned depressions 46, having the openings 47. An adjusting stop hood is detachably supported on the tube 45 and consists of the cup shaped shell 50, preferably of rubber, having the converging peak 51, the curvature of which vanishes with said tube.

A rubber tube 55 leads from a douche 65 bag, not shown, and connects with the inlet nipple 25. A rubber tube 56 has one end connected to the outlet nipple 27 and leads to the pan 60.

To use the syringe it is inserted, in place 70 and the depth of its entrance is controlled by the location of the adjusting and stop hood 50. Water or other fluid used flows from the tube 55 and enters the opening 26 of the nipple 25, on its way through the 75 injection tube 20. The fluid next enters the discharge chamber 36 of the outlet nozzle 35 and is discharged through the small outlet openings 38, and directed to the organ to be cleaned or treated. By reason of the 80 nipple 25 being larger than the nipple 27, pressure is automatically produced in the vagina which unfolds the folds thereof and balloons the same, until the fountain bag which supplies the cleaning fluid is completely emptied. The fluid on its return 85 enters the openings 47 of the tube 45 and flows through the annular space between said tube and the injection tube 20, and then enters the return fluid outlet chamber 28. 90 The outlet fluid then flows through the outlet nipple 27, the tube 56 and into the pan 60. The rate of discharge of the fluid through the tube 56 can be controlled, by 95 clamping any portion thereof. The adjusting and stop hood 50 prevents the injection fluid flowing to waste before performing its function.

A suction can be obtained with the syringe after being inserted in place by compressing the tube 55, when the weight of the fluid in the tube 56, produces a partial vacuum in the tube 45 and thereby a suction in said tube 45 draws the return fluid therethrough. This is made possible by reason of the stop hood 50 being of pliable material and adjustably supported on the tube 45 to permit its close contact with the body of the user.

Various modifications may be made in the 110

invention and the present exemplification is to be taken as illustrative and not limitative thereof.

Having described my invention what I desire to secure by Letters Patent and claim is:

In a vaginal syringe of the character described the combination of an injection tube, a tube fitting having one end detachably connected to one end of said injection tube, an inlet nipple for said fitting, an outlet nipple for said fitting of smaller diameter than the inlet nipple to automatically produce pressure in and unfold the folds of the vagina, when the fluid used in the syringe is being discharged, an outlet nozzle having recesses on its outer face detachably connected to the other end of the injection

tube, said nozzle having openings extending from said recesses to its interior, an outer tube having a plurality of recesses extending from its outer face with openings extending to its interior detachably connected to said tube fitting and to said nozzle and surrounding the injection tube and an adjusting stop hood coacting with the nozzles of different diameters to produce pressure in the vagina, consisting of a cup shaped shell of flexible material adjustably supported on the outer tube, said shell having formed therewith a converging peak that joins with said outer tube and vanishes therewith.

In testimony whereof I affix my signature.

HARRY MELDRUM.
